(57) **CLAIM**

The ornamental design for a television receiver, as shown and described.

DESCRIPTION

FIG. 1 is a perspective view of a television receiver showing our new design;

FIG. 2 is another perspective view thereof;

FIG. 3 is a front elevational view thereof;

FIG. 4 is a rear elevational view thereof;

FIG. 5 is a top plan view thereof;

FIG. 6 is a left side elevational view thereof;

FIG. 7 is a right side elevational view thereof.

FIG. 8 is an enlarged perspective view thereof showing a left half claimed portion of FIG. 1;

FIG. 9 is an enlarged perspective view thereof showing a right half claimed portion of FIG. 1;

FIG. 10 is an enlarged perspective view thereof showing a left half claimed portion of FIG. 2;

FIG. 11 is an enlarged perspective view thereof showing a right half claimed portion of FIG. 2;

FIG. 12 is an enlarged front elevational view thereof showing a left half claimed portion of FIG. 3;

FIG. 13 is an enlarged front elevational view thereof showing a right half claimed portion of FIG. 3;

FIG. 14 is an enlarged rear elevational view thereof showing a left half claimed portion of FIG. 4;

FIG. 15 is an enlarged rear elevational view thereof showing a right half claimed portion of FIG. 4;

FIG. 16 is an enlarged top plan view thereof showing a left half claimed portion of FIG. 5;

FIG. 17 is an enlarged top plan view thereof showing a right half claimed portion of FIG. 5;

FIG. 18 is an enlarged left side elevational view thereof showing a claimed portion of FIG. 6; and,

FIG. 19 is an enlarged right side elevational view thereof showing a claimed portion of FIG. 7.

The broken lines in the drawing depict environmental subject matter only and form no part of the claimed design. Dot-dash broken lines define the boundaries of, but not included in, the claimed design.

1 Claim, 19 Drawing Sheets
